MIRROR SUPPORT

Elizabeth Wagg Simons, 3306 Rowan Road,
Sedgefield, Greensboro, N.C.

Filed July 1, 1957, Ser. No. 669,359

2 Claims. (Cl. 248—28)

This invention relates generally to the class of supports and is directed particularly to improvements in supports designed for mounting framed bodies, such as mirrors, pictures or the like.

While the present invention may be employed effectively for mounting any type of frame or a body to be displayed or otherwise used, it is designed particularly for mounting mirrors upon dressers or other similar articles of furniture.

As is well known, mirrors are furnished in various sizes and shapes and when the same are to be positioned for use upon an article of furniture, such as a bureau, chiffonier, dressing table or the like, a means must be provided for securing the mirror in position so that such means will not show or so that no material amount of the support will show from the front. While supports have been provided heretofore which can be altered or adjusted to fit mirror frames or other frames of different heights, such adjustable supports require a considerable amount of manipulation to get them properly adjusted. It is accordingly a particular object of the present invention to provide a support for a mirror or the like which can be easily and quickly lengthened or shortened as may be desired to fit it to the height of the mirror frame and which can then be very easily tightened so that it will maintain its adjusted position effectively.

Another object of the invention is to provide a support for a frame for a body of the nature of a mirror, picture or the like which embodies an elongate rigid member or standard adapted to be secured to the back of a dresser or similar article of furniture and which has associated with it a second elongate member which is extensible to be attached to one side of the frame after fixing the other side to and against the front of the standard.

More specifically the invention is directed to a support for the purpose stated which embodies an elongate channeled body having a flat forward face and slotted at its rear side, with means in the lower end portion of the body for fixing it to a base structure such as a dressing table or the like, and other means for facilitating its attachment to the bottom portion of a frame and having at its opposite or upper end a longitudinally extensible second elongate member which is adjustably secured to the first member and which is designed to be fixed to the opposite or top part of the frame to be supported.

A further object of the invention is to provide a single elongate support of the general character above described which not only may be easily and quickly adjusted for length to accommodate it to frames of different sizes, but which will provide a rigid mounting which will not turn or have any movement after being secured to a base structure and to the frame which it is designed to support.

The invention will be best understood from a consideration of the following detail description taken in connection with the accompanying drawings forming part of the specification, with the understanding, however, that the invention is not confined to a strict conformity with the showing of the drawings but may be changed or modified

2

so long as such changes or modifications mark no material departure from the salient features of the invention as expressed in the appended claims.

In the drawings:

5 Fig. 1 is a view of the rear or back portion of an article of furniture and a mirror and showing one embodiment of the invention secured to the base structure and to the mirror;

10 Fig. 2 is a view in elevation on an enlarged scale of the front or forward side of the support shown in Fig. 1;

Fig. 3 is a longitudinal section through the support taken substantially on the line 3—3 of Fig. 2;

Fig. 4 is a transverse section taken substantially on the line 4—4 of Fig. 3 and on an enlarged scale;

Fig. 5 is a view corresponding to Fig. 1 but showing another embodiment of support in rear elevation;

Fig. 6 is a front elevation on an enlarged scale of the second embodiment shown in Fig. 5;

20 Fig. 7 is a longitudinal section taken substantially on the line 7—7 of Fig. 6;

Fig. 8 is a transverse section taken substantially on the line 8—8 of Fig. 6 and on an enlarged scale.

Referring now more particularly to the drawings, the description will first be confined to the embodiment of the invention illustrated in Figs. 1 to 4. It is understood, however, that the order of describing the embodiments in no way indicates the relative merits or values of the two embodiments as they both function with equal effectiveness.

25 Referring particularly to Fig. 1, the numeral 10 generally designates any conventional type of furniture upon which a mirror or other framed body might be mounted, as for example, this reference may designate a bureau, dressing table or the like, and it will be apparent that the view is of the rear of the article and the numeral 12 designates the top while the numeral 14 designates one of the transverse back braces which is secured horizontally between the back corner leg posts 16.

30 The numeral 18 generally designates a framed article such as a mirror or the like wherein the frame is made up of the top and bottom bars 20 and 21, respectively, and side bars 22.

The support shown in Fig. 1 and the succeeding Figs. 46, 2, 3 and 4, embodies an elongate rigid channel member which is generally designated 23 and which would, of course, be formed of steel or other suitable metal. This first elongate member 23 is of rectangular cross section as shown in Fig. 4 and embodies a front wall 24, the integral side walls 25, each of which joins a narrow inturned flange 26 forming a part of a back wall which is longitudinally slotted. In other words, the flanges 26 are in spaced parallel relation, thereby providing the rear slot 27 which extends throughout the length of the member as shown in Figs. 1 and 3.

55 The wall portion 24 has formed therethrough a means for facilitating securing the member vertically to the back of the article 10, which means comprises a plurality of apertures 28 formed through the wall 24 and longitudinally of the central part thereof, and in the lower end portion of the member there are also means above the series of apertures 28 for facilitating attachment of the member to the lower bar 21 of a frame, the last named means also comprising a series of apertures 29 extending longitudinally of the wall, as shown.

60 Extending into the channel member 23 from the upper end or that end remote from the apertures 28 and 29, is an end of a second elongate member which is generally designated 30 and which in this embodiment of the invention comprises a flat bar 31 of substantial thickness and of a width to fit relatively snugly between the sides 25 of the first member 23. This bar, while of substantial thickness so as to have the proper strength for the

job, is also resilient so that it may be flexed forwardly, as illustrated in Fig. 3, to facilitate attachment of the top end thereof to the top of the frame to be supported, after the lower part of the frame is secured to the first elongate member 23 as shown in Fig. 3.

The second elongate member 30 is positioned against the inner faces of the back flanges 26 and adjacent to the lower end of the bar 31 is an aperture 32 for the extension through the bar of the threaded shank portion 33 of a large flat headed screw 34 the head of which is designated 35. As shown in Fig. 4, the head of the screw is of a width to span the slot 27 and on the inner side of the second member 30 or of the bar thereof the threaded shank of the screw is engaged in a suitable resilient locking nut such as that generally designated 36 and which is preferably of the type known in the trade as a Tinnerman nut.

The top end of the front wall 24 of the first elongate member is provided with an aperture 37 and the top end of the second elongate member 30 has an aperture 38 therethrough. These apertures obviously are for the reception of securing elements, the aperture 38 being used when the member 30 is extended while if the article to be supported is of such height that it can be attached directly to the first member 23, then the second member 30 is slid down either to a point where the aperture 38 lies below the aperture 37 so that a securing element can be passed through aperture 37 into the article to be supported, or the apertures 37 and 38 could be aligned and the securing member passed through both.

Referring now to Figs. 5 to 8, inclusive, where the second embodiment of the support is illustrated, the numeral 39 generally designates an article of furniture while the numeral 40 generally designates a framed article which the support is designed to maintain in desired position on the underlying base article 39. The base article 39 and the supported article 40 are here shown as the same as those illustrated in Fig. 1 and designated respectively 10 and 18, and accordingly it is not believed that a detailed description of the several parts thereof is required to understand the application of the invention.

The second support comprises, like the first, the elongate rigid first member 41 of channel form which embodies a flat front wall portion 42, side walls 43, and the inturned back wall flanges 44 which are in edge spaced relation to form the slot 45.

The lower part of the member 41 is provided with means to facilitate the attachment or securing of the support to the back of the furniture article 39, which means is in the form of a multiplicity of apertures 46 formed through the wall 42 and extending lengthwise thereof.

Above the group of apertures 46 is a second group of apertures 47 which facilitate the attachment of the first member 41 of the support to the lower part or bottom bar of the frame 40.

The upper portion of the member 41 has the wall 42 thereof provided with the long slot 48 which cooperates in the manner hereinafter set forth with the back slot 45 for maintaining in longitudinally adjusted position the upper and shorter second elongate member which is generally designated 49.

The adjustable member 49 is of approximately the same cross sectional contour as the lower member 41. In other words, it is in the form of an essentially tubular body having a forward or front wall 50, side walls 51 and inturned spaced back wall flanges 52, the space between which flanges forms a slot 53 which, as shown in Fig. 8, is of approximately the same width as the slot 45 with which it aligns.

The front wall 50 of the second elongate member also has a long slot formed therein as indicated at 48'. This front slot 48' is approximately the same width as the front slot 48 and one end of the second member 49 is

slidably extended into the upper end of the first member 41, bringing the slots 48 and 48' into alignment to receive a friction holding means which is generally designated 54 and which is in the form of a screw or bolt having the long shank 55 and the flat head 56. As in the case of the screw or bolt 34, the head 56 of this second bolt is of sufficient size or diameter to span the slots 48 and 48' and the shank of the bolt is introduced through these slots from the front of the support and extends through and beyond the aligned back slots 45 and 51 to receive a wing nut 57, as illustrated. The wing nut may be threaded or drawn up on the shank 55 to bear directly against the flanges 44 of the first member 41 or preferably the shank 55 may have placed thereon metal washers 58 to position against the inner side of the front wall 50 of the second member in opposed relation with the head 56, with a spacer sleeve 59 positioned on the shank to bear at one end against one of the washers 58 and having its other end extending rearwardly through the back slots 45 and 51 to receive on its outer end the thrust of the wing nut. It will be seen from this that by loosening the wing nut the upper and lower members of the support can be relatively shifted to elongate or to shorten the support as may be desired to fit it to the mirror frame or other frame which it is to carry.

The upper end of the second or short one of the two members is provided with an aperture 60 to receive a securing element such as a screw or the like, which is threaded into the top bar of the frame.

In this second embodiment of the invention it will be seen that the two walls 42 and 50 of the two members are parallel and positioned one against the other so that when the support is mounted on the underlying base or article of furniture the forward faces of these walls 42 and 50 can be placed flat against the back of the frame or in contact with the upper and lower bars thereof corresponding to the bars 20 and 21 of the frame 18.

In Fig. 1 the first embodiment of the support is shown with the lower portion of the first member 23 positioned with the face of the wall 24 against the back of the article of furniture and securing screws 61 are extended through the proper apertures 28 to engage in the back edge of the top 12 of the article and in the bar 14 thereof.

The frame 18 is positioned against the forward face of the wall 24 with the bottom bar 21 in position with respect to one of the apertures 29 to receive a securing screw 62 which is extended through the proper aperture and the support is attached to the frame by loosening the binding screw or friction holding device 34 and sliding the second elongate member 30 upwardly or downwardly as may be necessary to bring the aperture 38 in line with the top bar 20 of the frame whereupon a securing element such as a screw 63 is passed through the aperture into the adjacent frame part. The friction holding device 34 may then be tightened so as to prevent a relative movement between the parts 23 and 30.

Due to the fact that the second member 30 is flat and flexible, it will be seen that it may be readily bent to bring the aperture 38 into the proper position to receive the holding element 63, as illustrated in dotted lines in Fig. 3.

The manner of employing the second embodiment of the invention is essentially the same as described in connection with the first. Holding screws 64 are passed through the proper apertures 46 of the first elongate member 41 and another holding element 65 is passed through one of the apertures 47 for engagement in the bottom bar of the frame 40. When the friction holding element 54 is sufficiently loosened, the member 49 can be adjusted in the upper end of the member 41 to bring the aperture 60 into the proper position with respect to the top bar of the frame 40 to receive the securing screw or other securing element 66 after which the wing nut 57 is tightened up to firmly lock the two members 41 and 49 together.

In this second embodiment of the invention the upper end of the wall 42 of the first member is also provided with an aperture as at 67, which may be aligned with the aperture 60 where the frame to be supported is of such height that this aperture 67 alone or the two apertures 60 and 67 may be used to receive the holding screw 66.

From the foregoing, it will be seen that there is provided in the present invention in the two embodiments illustrated and described, a support which can be easily and quickly adjusted at its upper end or in the upper end portion thereof to fit frames of different heights and also the device after being so adjusted and after having the two parts secured together by the friction holding means, provides a rigid mounting for the article to be set up.

While the invention has been illustrated as being used singly for the support of a framed body such as a mirror, obviously if the article to be supported is of material width, two of these supports may be mounted upon the back of the supporting base structure in spaced parallel relation to be secured in their upper end portions across the back of the wider article.

I claim:

1. A support for a frame for a body such as a mirror, picture and the like, said support comprising an elongate rigid first member, said first member being formed of a channel member having a flat back wall, longitudinal side walls, and inturned spaced flanges bordering the side walls and forming a longitudinal slot opposite from the back wall, a second elongate member slidably inserted into one end of the first member, said second member being of the same cross sectional form as the first member and relatively snugly fitting therein with the back walls of the members slidably engaging one upon the other, a releasable coupling binding together the engaged back walls and operable through the slots of the members to secure the second member in a position of longitudinal adjustment on and relative to the first member, means for facil-

tating securing both members to opposite side portions of a frame to be supported, means for facilitating securing the first member adjacent to the end thereof remote from the second member to a base support, the said two members having longitudinal aligned slots in the back walls thereof and said releasable coupling comprising a securing member having a threaded shank carrying a head on one end with said shank extending through said aligned back wall slots and projecting from the opposite side of the two members through the slots thereof formed by the inturned spaced flanges with the head of said securing member spanning the back wall slots and bearing upon the outer side of the back wall of the first member, a sleeve loosely encasing said shank and having an end portion projecting

15 through the slots formed by said spaced flanges of the first and second members and a nut threaded on the end of said shank and engaging the adjacent end of the sleeve for applying thrust through the sleeve against the inner side of the back wall of the second member whereby to 20 frictionally clamp said back walls of the first and second members together.

2. The invention according to claim 1, with friction members encircling the shank of said securing member and interposed between the other end of said sleeve and 25 the inner side of the back wall of the second member and spanning the longitudinal aligned slots of the first and second members.
